Attorney

UNITED STATES PATENT OFFICE.

GEORGE KOLLSTEDDE, OF PROVIDENCE, RHODE ISLAND, ASSIGNOR TO V. E. BLACK COMPANY INCORPORATED, A CORPORATION OF RHODE ISLAND.

BEAUTY BOX.

Application filed February 12, 1921. Serial No. 444,380.

To all whom it may concern:

Be it known that I, GEORGE KOLLSTEDDE, a citizen of the United States, residing at Providence, in the county of Providence and 5 State of Rhode Island, have invented certain new and useful Improvements in Beauty Boxes, of which the following is a specification.

My invention relates to containers for 10 powder or cosmetics adapted for beautifying.

The essential objects of my invention are to avoid the use of solder whereby the parts of the structure are liable to discoloration 15 and injury; to lessen the labor and expense of construction and assemblage of parts; and to attain these and other ends in a simple and strong structure.

To the above ends essentially my invention 20 consists in such parts and in such combinations of parts as fall within the scope of the appended claims.

In the accompanying drawings which 25 form a part of this specification

Figure 1 is a perspective view of my 30 novel box in open position,

Figure 2, a rear perspective view of the 35 housing portion removed,

Figure 3, an enlarged perspective view of 40 the hinge,

Figure 4, a bottom plan view of the 45 housing portion, and

Figure 5, a central transverse section of 50 the box in closed position.

Like reference characters indicate like 55 parts throughout the views.

The body 8 of my box is in this instance oval, and comprises a bottom wall 9 and a 60 peripheral side wall or flange 10. The latter

is provided in the middle of its front portion with an opening 12, diametrically opposite to which are hinge sleeves 13 formed on the edge of the wall. A cover 14 for the 65 box comprises a top wall 15 and a peripheral

side wall or flange 16 provided with a cavity 17 midway the length of its front portion. Integral with its rear edge, opposite the 70 cavity, are hinge sleeves 19. A pintle 20 in the sleeves 13 and 19 completes a hinge between the body and cover. Resting against 75 the cover top 15 is a mirror 22 engaged by a frame or retaining plate 23 supported by indentations or projections 24 in the flange 16.

A housing member 26 comprises a flat top 80 plate 27 and a peripheral downwardly di-

rected flange or side wall 28 integral therewith. In one piece with the top 27 are pockets or cups 30 comprising bottoms 31 and sides 32. In this instance the pockets are two in number and are arranged one on each side 60 of the center of the top plate in longitudinal alignment with each other. Midway the front of the wall 28 are upper and lower openings 34 and 35, and opposite these the flange has a horizontal depression or 65 socket 37.

The housing member is cut and drawn up in all its details, by suitable dies, from a single thin sheet of metal, and the wall 28 is somewhat resilient. Neither the pockets 70 nor the flange, therefore, require soldered connection.

Within the housing fast to the wall 28 by rivets 39 in one end is a flexible horizontal plate 40 having upon its free end laterally 75 extending upper and lower ears 41 and 42. The ear 41 passes through the opening 34 at a point above the body wall 10, and when the cover is closed resting on wall 10 the ear enters the cavity 17. The ear 42 passes 80 through the openings 35 and 12. The vibratory plate or finger 40 has contacting with its rear face a curved flat spring 44 whose end margins abut against the pockets 30 and thus the spring is held in position by friction without the use of solder. In unlatching the cover the operator presses inwardly with his thumb or finger the ear 42, and the spring 44 assists the yielding plate 40 to return the latch into original position with 85 the finger 41 in its seat 17 thus maintaining the cover in closed position.

The resiliency of the flange 28 permits it to yield during the assembling operation to pass the hinge and maintain the hinge in 95 its seat after assemblage. The engagement of the parts thus interlocked is not sufficiently great to prevent the disassemblage of the parts, if desired, manually.

In this instance upon opposite ends of the 100 wall of the body are eyes 46 adapted to receive the ends of an extension chain.

I claim:

1. In a box of the character set forth, a hollow body, a cover, a hinge connecting the 105 body and cover, and a housing comprising a top, a pocket in the top, and a resilient peripheral flange slidably embraced by the body and provided with a socket receiving the hinge.

2. In a box of the character set forth, a body including a peripheral wall provided with an opening, a cover pivotally mounted on the wall provided with a cavity, a housing comprising a top depending pockets in the top, and a depending peripheral flange detachably embraced by the wall, a vibratory

plate fast to the flange, ears on the plate registerable in the opening and in the cavity, and a flat spring resting against the pockets 10 and the plate.

In testimony whereof I have affixed my signature.

GEORGE KOLLSTEDE.
